SELECTIVE COIN OPERATED SWITCH

Filed Sept. 5, 1946

Fig. 2.

INVENTOR.
JOSEPH H. KNAPP

BY

Joe Stover
ATTORNEY

and I declare that I invented the following and that I desire to secure a patent therefor:

My invention relates to devices for making, breaking or changing the connections in an electric circuit and adapted to be operated by the insertion of a coin in a slotted wall of a coin receiving chute adjacent thereto.

UNITED STATES PATENT OFFICE

SEARCHED

2,477,133

SELECTIVE COIN OPERATED SWITCH

Joseph H. Knapp, Kansas City, Mo., assignor to
C. Earl Hovey, trustee, Kansas City, Mo.

Application September 5, 1946, Serial No. 694,841

1 Claim. (Cl. 194-9)

1

This invention relates to devices for making, breaking or changing the connections in an electric circuit and adapted to be operated by the insertion of a coin in a slotted wall of a coin receiving chute adjacent thereto.

One of the most important objects of this invention is the provision of a selective coin operated switch device in the nature of that disclosed by U. S. Letters Patent No. 2,213,845, dated September 3, 1940, in which a coin operated actuating means is provided for the number of push rods for moving a contact into engagement with a stationary contact.

Still further objects of this invention include the provision of a switch device wherein the series of reciprocable plungers for closing corresponding circuits are each actuated by a specially formed lever pivotally mounted on a single shaft, and each having a portion thereof engageable by a coin; the provision of a coin receiving chute having openings formed therein for slidably receiving a portion of the levers; means for mounting the levers on said shaft; and the provision in one wall of the chute of a series of slots for receiving the coin to move the levers as the coins are moved against a portion of the lever covering the slot.

With the foregoing and many other objects in mind, the invention will now be described by referring to the accompanying drawing, wherein:

Fig. 1 is a fragmentary top plan view of the selective coin operated switch device made in accordance with my present invention, parts being broken away to reveal details of construction.

Fig. 2 is an end elevational view thereof.

Fig. 3 is a cross-sectional view thereof taken on line III-III of Fig. 1; and

Fig. 4 is an edge elevational view thereof looking from the right in Fig. 1, parts being broken away for clearness.

The operation of my present invention will become clear by setting forth briefly the broad idea embodied in Patent No. 2,213,845, covering a switch. That switch included a number of push rods or plungers 10 slidably mounted in slots formed in a pair of base members 12 and 14, and having a single locking bar 16 threaded through slots provided in the plungers 10. The operation is such as to cause the bar 16 to lock any one of plungers 10 against outward movement as the same is moved inwardly toward one end of its path of travel. Movement of any one of the other plungers inwardly causes the held plunger to be released and move to the point of beginning through the action of a spring provided for each plunger 10. A number of spring contacts, not here

shown, are carried by an insulated block adjacent the plungers, and an equal number of contacts carried by the plungers are brought into respective interengagement to close a series of circuits in which the switch is interposed.

All of the foregoing mechanism is shown in Fig. 2 as being held in position by a bracket 17 having a pair of opposed, downwardly projecting flanges 18 and 20, which in turn are attached to a plate 10 22 through the medium of bolts 24. This plate 22 is shown mounted on one face 24 of a machine with which the device is to be used, or other suitable support, that is provided with an opening 26, and the plate 22 encircles this opening 26 and is fixed to the face 24 by screws 28 or other fastening means.

A pair of legs 30 and 32 fused to the bracket 17 as at 34 carry a substantially U-shaped chute 36 on the free ends thereof that extends longitudinally below the plate 22 near one edge thereof. A series of coin receiving slots 38 in the plate 22 communicate with the chute 36, and a number of substantially L-shaped levers 40, each have one leg 42 thereof disposed in underlying relation with 15 a respective slot 38.

A tubular portion 44 is formed at the bight of each lever 40 through which portions 44 a shaft 46 passes to pivotally mount the levers 40, and a channelled support 48 welded to the bracket 17 is disposed in embracing relation with each lever 40 for holding the same against lateral displacement on the shaft 46. These supports 48 serve to mount the shaft 46 through the medium of transverse holes provided in the down-turned flanges thereof.

A leg 50 of the lever 40 extending below the shaft 46, engages a respective plunger 10 when the lever 40 pivots on the shaft 46, and a spring 52 coiled about the shaft 46 has the legs thereof bearing against the bracket 17 and the bight thereof against the lever 40 to yieldably maintain the leg 42 of the lever 40 against the inner face of the plate 22. There is a spring 52 for each lever 40, and a pair of aligned openings 54 and 56 for 45 each lever 40 provided in the chute 36, slidably mount the legs 42 of levers 40.

It is clear from the foregoing that as a coin 54 is inserted in one of the slots 38 in the plate 22, this coin 54 will engage a portion of the leg 42 that extends across the slot 38. As the lever 40 pivots on the shaft 46, the leg 50 thereof will engage a corresponding plunger 10 and move the same inwardly to a point where a circuit is closed and the plunger 10 is engaged by the bar 16 to hold the same against outward movement. As

the coin 54 is moved inwardly into the chute 36, for passage therein to a coin box, not here shown, the leg 42 of the lever 40 will be returned to a position underlying its slot 38 of the plate 22, by the action of its spring 52.

When a coin 54 is inserted in another slot 38 to actuate another plunger 10, the bar 16 will release the first plunger 10 and hold the latter plunger 10 in operative position in the manner set forth in the aforesaid Patent No. 2,213,845.

A panel 56 mounted on the plate 22 carries suitable indicia to number or name each of the slots 38 whereby the operator is informed as to the manner in which the machine with which the switch is used will operate depending on the lever 40 that is actuated.

Obviously, coin operated switch devices having appearances, form and modes of operation different from those above specified may be made without departing from the spirit of the invention or scope of the appended claim.

Having thus described the invention, what I claim as new and desire to secure by Letters Patent is:

In a selective coin operated switch device having a reciprocable plunger; structure for actuating said plunger comprising a coin-receiving chute having a slot formed therein; a shaft; a substantially L-shaped lever pivotally mounted on the shaft, one leg of said lever extending into said chute, the other leg thereof being engageable with said plunger to actuate the same as a coin is inserted in the chute through the slot and

against said one leg of the lever, said chute being U-shaped in cross sectional contour and having a pair of aligned openings, one opening being formed in each leg thereof respectively, said one leg of the lever traversing the chute through said openings and being slidable therein; and means for yieldably holding the one leg flatly against one face of the chute across the slot and in covering relation to a portion of the latter.
